UNITED STATES PATENT OFFICE

104,672

DESIGN FOR A RING MOUNTING

Arthur Alvin Ahlquist, Norwood, R. I., assignor to Uncas Manufacturing Company, a corporation of Rhode Island

Application April 13, 1937, Serial No. 68,730

Term of patent 14 years

To all whom it may concern:

Be it known that I, Arthur Alvin Ahlquist, a citizen of the United States, residing at Norwood, in the county of Kent and State of Rhode Island, have invented a new, original, and ornamental Design for a Ring Mounting, of which the following is a specification, reference being had to the accompanying drawing, forming a part thereof.

Fig. 1 is an elevation; and
Fig. 2 is a section on line 2—2 of Fig. 1 with the dotted lines omitted for convenience, showing a ring mounting, the dominant part being shown in full lines.

I claim:

The ornamental design for a ring mounting substantially as shown and described.

ARTHUR ALVIN AHLQUIST.
